COMBINED WINE DISPENSER AND CART

Irving L. Metzner, Dover, and Daniel O'Connell, Pound Ridge, N.J., assignors to Colgate-Palmolive Company, New York, N.Y.

Filed Jan. 17, 1973, Ser. No. 324,377

Term of patent 14 years

Int. Cl. D9—01; D12—02
U.S. Cl. D94—3 C

FIG. 1

FIG. 2

FIG. 3

FIG. 4

FIG. 1 is a front perspective view of a combined wine dispenser and cart showing our new design;

FIG. 2 is a right side elevational view thereof;

FIG. 3 is a left side elevational view thereof; and

FIG. 4 is a rear elevational view thereof.

The bottom is flat and not ornamented.

We claim:

The ornamental design for a combined wine dispenser and cart, as shown and described.
